UNITED STATES PATENT OFFICE

RAY E. DUNHAM, OF BEREAL, OHIO, ASSIGNOR TO THE DUNHAM COMPANY, OF BEREAL, OHIO, A CORPORATION OF OHIO

CORE-MOLDING MECHANISM

Application filed January 28, 1929. Serial No. 335,445.

My invention relates to core molding mechanism, and the principal object of my invention is to provide new and improved mechanism of this type. In the drawings accompanying this specification and forming a part of this application I have shown, for purposes of illustration, one form which my invention may assume, and in these drawings:

Figure 1 is a side elevation of the embodiment of my invention herein illustrated;

Figure 2 is a front elevation of the device shown in Figure 1;

Figure 3 is a rear elevation of the device shown in Figures 1 and 2;

Figure 4 is a top plan view of the embodiment of my invention herein illustrated;

Figure 5 is a section on the line 5—5 of Figure 1;

Figure 6 is a section on the line 6—6 of Figure 1;

Figure 7 is a view similar to Figure 4 but showing the cope section swung over into sand receiving position;

Figure 8 is a view similar to Figure 7 but showing the core forming inserts advanced and the core spider in place;

Figures 9 through 11 are views similar respectively to Figures 1, 2, and 7, but showing the cope section swung into sand receiving position and the core supporting frame in position; while

Figure 12 is a detail illustrating the connection by which the core supporting frame is attached to the core spider.

The embodiment of my invention herein shown comprises a frame 11 provided with a base 12 supported for movement from place to place by means of four wheels 13 and carrying an annular upwardly extending section 14 terminating in a face plate 15 and supporting for vertical reciprocation relative thereto a table 16 terminating in a face plate 17 having its upper face substantially flush with the upper face of the face plate 15 of the frame 11 when the table 16 is in elevated position.

In the embodiment of my invention herein shown the table 16 is reciprocably mounted in the annular section 14 of the frame 11 by means of four V-ribs 18 projecting from the table 16 adjacent the corners thereof and riding in corresponding V-grooves 19 formed in runners 20 adjustably secured to bars 21 forming parts of the annular section 14 of the frame 11 by means of machine screws 22 adjustable to bring the V-grooves 19 in the runners 20 into registration with the V-ribs 18 on the table 16.

In the embodiment of my invention herein shown the weight of the table 16, and the weight of the parts carried thereby, is almost counter-balanced by means of a pair of springs 23 extending between the lower face of the table 16 and the upper face of the base 12 of the frame 11 surrounding rods 24 which extend downwardly from the lower face of the table 16 through cooperating apertures 25 formed in bosses 26 present on the ends of the base 12 of the frame 11 and are effective to additionally guide the table 16 relative to the frame 11, and the table 16 is reciprocated relative to the frame 11 by means of four links 27 pivoted at their upper ends

to the four corners of the table 16 and at their lower end to bell-crank levers 28 mounted upon shafts 29 and 30 supported in the frame 11, having their lower arms connected by means of links 31, and operated in unison because of the interconnection through the links 31 and by rotation of the shaft 29 by means of a suitable operating lever 32 secured thereto.

Projecting from the upper face of the table 16 are a pair of posts 33 to which are pivotally connected arms 34 secured to the drag section 35 and therefore supporting the drag section for pivotal movement about the pivot pins 36 uniting the hubs of the posts 33 and arms 34, while rising from the face plate 15 of the frame 11 are a pair of posts 37 to which are pivoted a pair of arms 38

connected to the cope section 39 to support the cope section 39 for pivotal movement about the pivot pins 40 connecting the hubs of the posts 37 and arms 38 and alined with the drag section pivot pins 36 when the table 16 is in its fully elevated position relative to the frame 11.

In the particular embodiment of my invention it is desired that the core contain indentations which cannot be formed directly by the drag and cope sections 35 and 39 without preventing stripping of the core, and accordingly must be formed by removable or retractable elements movable relative to the drag and cope sections 35 and 39, and accordingly in the embodiment of my invention herein shown the cope section 39 contains four retractable elements 41 movable between advanced and retracted position by means of four levers 42 pivoted at their outer ends to the four retractable elements 41 and formed at their inner end as eccentric straps surrounding eccentrics 43 fixed to a shaft 44 mounted in ribs 45 on the outer face of the cope section 39 and operated by means of a handle 46 effective as will readily be understood to simultaneously move all of the elements 41 between advanced and retracted position, and the drag section 35 is provided with similar elements 47 similarly operated. The embodiment of my invention herein shown also contemplates the use in the core, in the drag section of the core, of a core spider 48, and accordingly the drag section 35 is provided with recesses 49 for the reception of the core spider 48.

In operation the cope and drag sections are opened to the position shown in Figures 7 and 8, the elements 47 and 41 are advanced into the position shown in Figure 8, the core spider 48 is inserted into position as shown in Figure 8, and the sand is rammed into both the cope section 39 and the drag section 35, then both the drag section 35 and the cope section 39 are swung about the pivot pins 36 and 40 into vertical hooking position abutting each other, after which the cope section 39 and the drag section 35 are together swung further about the pivot pins 36 and 40 until the drag section 35 has returned to its original position and the cope section 39 is positioned inverted atop the drag section 35, as shown in Figures 1 through 4. The elements 41 of the cope section 39 are then retracted, and then the table 16 and the drag section 35 are depressed to strip the core from the cope section 39, the cope section 39 being held against further downward movement by the engagement of its free edge with pins 50 rising from the face plate 15 of the frame 11, and the cope section 39 being thereafter swung back into its initial sand receiving position ready for the reception of sand for the next core. The table 16, the drag section 35, the core spider

48, and the core surrounding the core spider 48, are then returned to elevated position, after which a core supporting frame 51 is placed in position resting at one side upon the cope section pivot posts and arms 37 and 38 and at the other side upon the pins 50, and the core supporting frame 51 is connected to the core spider 48, the elements 47 of the drag section 35 are retracted, and the table 16 and drag section 35 are again lowered to leave the core supported from the core supporting frame 51 stripped also from the drag section 35, after which the core may be transported by the core supporting frame 51, particularly by means of handles 52 projecting therefrom, into position within the mold for which the core has been prepared.

In the embodiment of my invention herein shown the core supporting frame 51 is quickly detachably connected to the core spider 48 by means of a pair of pins 53 positioned in apertures 54 extending vertically through the two sides of the core supporting frame 51, normally held in elevated position by means of springs 55 compressed between annular shoulders 56 extending inwardly in the apertures 54 adjacent the lower ends thereof and collars 57 secured to the pins 53 in position to overlie the tops of the bores 34, and provided at their lower ends with cross pins 58 adapted to enter through slots 59 in the corresponding arms 60 of the core spider 48 into circular recesses 61 with which the slots 59 communicate, and to then be rotated, by rotation of the handles 62 connected to the upper ends of the pins 53, into position underlying the top walls of the circular recesses 61 laterally of the slots 59 the collars 57 serving then to support the pins 53 from the core supporting frame 51; and the core supporting frame 51 is registered with the core by means of pins 63 projecting upwardly from the drag section 35 in position to engage within forks 64 projecting from the ends of the core supporting frame 51 and operable later to register the core supporting frame 51 and the core carried thereby with the mold into which the core is being positioned.

With the embodiment of my invention herein shown I am able to make the core entirely of green sand, and to make and strip the core on a single machine, and by means of a core support suitable for transporting the core to the mold to which it is to be inserted, and accordingly it will be apparent that the embodiment of my invention herein shown and described accomplishes at least the principal object of my invention. At the same time it will also be understood by those skilled in the art that the particular embodiment of my invention herein shown embodies advantages other than those particularly pointed out or suggested herein,

and also that this particular embodiment of my invention may be variously changed and modified without sacrificing the advantages thereof or departing from the spirit of my invention, and it therefore will be understood that the disclosure herein is illustrative only and that my invention is not limited thereto.

I claim:

- 10 1. Core molding mechanism, comprising: a frame; a table; means for effecting substantially vertical reciprocation of said table relative to said frame; a drag section and a cope section mounted respectively on said table and on said frame and movable relative to each other into and out of cooperating position; and means, becoming operable as said sections are moved out of cooperating position, for supporting the core independently 15 of said drag section.
- 20 2. Core molding mechanism, comprising: a frame; a table; means for effecting substantially vertical reciprocation of said table relative to said frame; a drag section mounted on 25 said table; a cope section mounted on said frame and movable into and out of position cooperating with said drag section; and means, becoming operable as said cope and drag sections are moved out of cooperating 30 position, for supporting the core independently of said drag section.

3. Core molding mechanism, comprising: a frame; a table; means for effecting substantially vertical reciprocation of said table relative to said frame; a drag section mounted on 35 said table; a cope section pivoted on said frame and oscillatable into and out of position cooperating with said drag section; and means, becoming operable as said cope and 40 drag sections are moved out of cooperating position, for supporting the core independently of said drag section.

4. Core molding mechanism, comprising: a frame; a table; means for effecting substantially vertical reciprocation of said table relative to said frame; a drag section and a cope section mounted respectively on said table and on said frame and movable relative to each other into and out of cooperating position; and means, becoming operable as said sections are moved out of cooperating position, for supporting the core independently of said drag section, and operable also for 50 transporting said core from said core molding mechanism to the mold.

5. Core molding mechanism, comprising: a frame; a table; means for effecting substantially vertical reciprocation of said table; a drag section and a cope section mounted respectively on said table and on said frame and movable relative to each other and said table into and out of cooperating position; and means, becoming operable as said sections are 60 moved out of cooperating position, for sup-

porting the core independently of said drag section.

6. Core molding mechanism, comprising: a frame; a table; means for effecting substantially vertical reciprocation of said table relative to said frame; a drag section pivoted to said table movable to booking position; and a cope section pivoted to said frame on an axis alined with the pivotal axis of said drag section in one relative reciprocatory position of said table and said frame, and movable from sand receiving position opened from said drag section through said booking position to inverted position atop said drag section.

7. Core molding mechanism, comprising: a frame; a table; means for effecting substantially vertical reciprocation of said table relative to said frame; a drag section pivoted to said table movable to substantially vertical booking position; and a cope section pivoted to said frame on an axis alined with the pivotal axis of said drag section in one relative reciprocatory position of said table and said frame, and movable from substantially horizontal sand receiving position opened from said drag section through said substantially vertical booking position to inverted position atop said drag section.

8. Core molding mechanism, comprising: a frame; a table; means for effecting substantially vertical reciprocation of said table; a drag section pivoted to said table movable to booking position; and a cope section pivoted to said frame on an axis alined with the pivotal axis of said drag section in one relative reciprocatory position of said table and said frame, and movable from sand receiving position opened from said drag section through said booking position to inverted position atop said drag section.

9. Core molding mechanism, comprising: a frame; a table; means for effecting substantially vertical reciprocation of said table relative to said frame; a drag section pivoted to said table movable to booking position; a cope section pivoted to said frame on an axis alined with the pivotal axis of said drag section in one relative reciprocatory position of said table and said frame, and movable from sand receiving position opened from said drag section through said booking position to inverted cooperating position atop said drag section; and means, becoming operable as said cope and drag sections are moved out of cooperating position, for supporting the core independently of said drag section.

10. Core molding mechanism, comprising: a frame; a table; means for effecting substantially vertical reciprocation of said table relative to said frame; a drag section pivoted to said table movable to substantially vertical booking position; a cope section pivoted to said frame on an axis alined with the pivotal axis of said drag section in one relative recip-

rocatory position of said table and said frame, and movable from substantially horizontal sand receiving position opened from said drag section through said substantially vertical booking position to inverted cooperating position atop said drag section; and means, becoming operable as said cope and drag sections are moved out of cooperating position, for supporting the core independently of said drag section.

10 In testimony whereof I hereunto affix my signature.

RAY E. DUNHAM.
